(57) **CLAIM**

The ornamental design for an ice cream scoop, as shown and described.

DESCRIPTION

FIG. 1 is a front perspective view of the ice cream scoop in a first configuration showing one aspect of my new design;

FIG. 2 is a front view thereof;

FIG. 3 is a side view thereof;

FIG. 4 is a top view thereof;

FIG. 5 is a bottom view thereof; and,

FIG. 6 is a front perspective view of the ice cream scoop in a second configuration with an ice cream puck and cone shown in broken lines.

The broken lines are for illustrative purposes only and form no part of the claimed design.
